United States Patent Office.

LEONCE FRANCIS DANDRE, OF PARIS, FRANCE.

Design No. 4,399, dated October 11, 1870.

DESIGN FOR AN OIL-CLOTH PATTERN.

The Schedule referred to in these Letters Patent and making part of the same.

I, LEONCE FRANCIS DANDRE, from Paris, France, now residing in New York, No. 67 East 10th street, State of New York, have invented and produced a new and original Drawing for Oil-Cloth, of which the following is a specification.

The nature of my design is fully represented in the accompanying new design illustrations, and consists, specially, in strips of equal width each, as shown in fig. 1 and fig. 2, disposed in the length of the piece of manufactured oil-cloth, which must have eight, ten, twelve, &c., strips, according to its width. Those strips represent, alternately, the one an imitation of wood, oak and black walnut, to obtain the same effect as the inlaid floor which is made with those two kinds of wood.

Description of the Accompanying Drawing.

Figure 1 is the drawing in natural size of my invention.

Figure 2 is a drawing in reduction of the same, showing the general effect of the alternating strips.

Claim.

I claim as my invention—

The design for oil-cloth, composed of strips of equal width, imitating the wood, oak and black-walnut, alternately, as described and shown.

LEONCE FRANCIS DANDRE.
